CLOTHES WASHING MACHINE

Filed Jan. 28. 1929

UNITED STATES PATENT OFFICE

JAMES B. KIRBY, OF WEST RICHLAND, OHIO

CLOTHES-WASHING MACHINE

Application filed January 28, 1929. Serial No. 335,490.

REISSUED

This invention relates to clothes washing machines and has for its object the provision of a new, improved, and simplified oscillating agitator which shall wash the clothing at least as effectually as heretofore, and shall also effectually prevent articles of clothing from working underneath the agitator where they may be torn and abraded by contact with the bottom of the tub. Another object of the invention is the provision of an agitator which shall to some extent tend to draw the clothes into operative relation with its upper surface; the provision of an agitator which shall be self-draining and devoid of pockets in which washing liquid may collect; while further objects and advantages of the invention will become apparent as the description proceeds.

In the drawings accompanying and forming a part of this application I have shown certain physical forms in which my inventive idea can be embodied. Fig. 1 is a vertical sectional view through a preferred form of my improved agitator showing the same in operative position with reference to the bottom of a tub or washing compartment; Fig. 2 is a top plan view of the agitator shown in Fig. 1; and Figs. 3 and 4 are sectional views of modified forms of my invention, the form shown in Fig. 3 being copied from my application Serial No. 694,899, filed February 25, 1924, and that shown in Fig. 4 being copied from my application Serial No. 281,455, filed May 29, 1928; and Fig. 5 is a section taken on the line 5—5 of Fig. 4.

The washing machine here shown for purposes of illustration comprises a liquid-holding tub or casing having a bottom wall 1, and a side wall 2, the former having at its center a vertical, hollow, bearing-sleeve 3 which preferably rises more or less above the bottom as shown at 4 in Fig. 1 and 4^a in Fig. 4. In Figs. 1 and 3 the center part of the bottom 1 is elevated gradually as shown at 5 to define a kind of shallow cone, although in Fig. 4 this portion is left flat. In each case, however, this central portion is surrounded by a shallow annular depression 6 adapted to

catch such articles as buttons, pins, marbles and the like.

Rotatably journaled in the sleeve 3 is an upright shaft 7 formed at a point above the sleeve 3 with a suitable driving head 8 on which the agitator is detachably mounted. In the form of the invention illustrated in Figs. 1 and 2 this agitator comprises a downwardly flaring, circular plate 9 formed at its center with a hollow hub 10 which constitutes a socket for the driving head 8, and also formed on its upper face with clothes rubbing and liquid agitating provisions of any suitable number and shape. In the present embodiment I have represented these as three radiating round-topped humps 11 of considerable size, although it is equally within my invention to use only one, or two, or even more than three, and to make them of any desired shape, size and spacing. The bottom of the plate 9 is formed with a plurality of depending radial blades 12, to which is tightly secured a circular shield-plate 13, spaced from the plate 9 so as to define a liquid passage. To hold this shield plate in place I have shown the plate 9 as formed at its center with a depending cylindrical skirt 14 spaced from the inner ends of the blades 12, but extending beyond those blades in such wise as to enable it to project through a circular aperture in the center of the plate 13, and afterwards to be spun over as shown at 15 to hold said plate tightly in place. The plate 13 preferably slants outwardly from the hub so as to shed water freely. I have shown the outer edge of the plate 9 as formed with a depending circumferential flange 16 overlapping the ends of the blades 12, in which case the plate 13 is terminated at a sufficient distance from this flange to define a peripheral slot 17 allowing the egress of washing liquid. The plate 9 is formed in or adjacent to the hub 10 with perforations 18 for the admission of washing liquid. The shaft 7 being oscillated vigorously about its axis as customary in such machines, the centrifugal force exerted upon the adjacent liquid by the blades 12 ejects the same beneath the margin of the plate 9 and over the bot

tom of the tub, thereby effectually opposing the ingress of articles of clothing beneath the agitator. Also the ingress of liquid through the aperture 18 tends in some degree to draw the clothing articles down upon the top of the agitator where they are the more effectually acted upon.

In the form of the invention shown in Fig. 3 the plate 9^a is formed at its top with a plurality of plain radial blades 11^a. Perforations 18^a allow ingress of liquid through the plate near the center whence it is ejected peripherally by the action of the blades 12^a with which the bottom of that plate is provided. No bottom plate is used but the bottom-blades sweep closely over the bottom 5 of the tub.

In the form of the invention shown in Fig. 4 the exterior of the driving head 8 is formed with a depending, hollow, cylindrical sleeve 20 surrounding and spaced from the upper end of the sleeve 4^a and forming therewith an air bell. The lower end of the sleeve 20 is formed with spaced fingers 21 receiving in steadyng relation the cylindrical inner wall 22 of the hollow hub 24. At its lower end this hub is flared outwardly to produce a circular plate 25. The hub is formed exteriorly with a plurality of spaced 30 radial blades 26, and at the bottom of the plate 25 is also provided a plurality of radial vanes 27. Secured to the bottom faces of these vanes is a circular plate 28 closely overlying the bottom 1 of the tub and having a central aperture 29 through which the sleeve 4^a passes freely. The body of the hub is formed between the ribs 26 with perforations 30 for the ingress of washing liquid which is ejected by the vanes 27. The latter in Fig. 4 project laterally beyond the disk 25 to assist in the washing action.

As a result of the currents of liquid produced by this agitator the clothes are brought into close engagement with the washing part 45 thereof and at the same time deflected away from the gap beneath it, thereby preventing injury to the clothing while permitting wide manufacturing tolerance. Also the device is free from danger of catching buttons and 50 other foreign articles, or of retaining washing liquid. It will be understood that many changes in detail can be made within the scope of my invention and I do not limit myself as specifically recited in my several claims 55 which I desire may be construed broadly, each independently of limitations contained in other claims.

Having thus described my invention what I claim is:

60 1. In a clothes washing machine, in combination a tub, an agitator located therein adjacent to the tub bottom and oscillatable about a vertical axis, said agitator underlying the clothing in said tub, and means carried by said agitator and actuated by the os-

cillation thereof for discharging liquid laterally thereof close to the tub bottom whereby ingress of articles of clothing beneath the agitator is opposed.

2. In a clothes washing machine, in combination a tub, an agitator located therein adjacent to the tub bottom and oscillatable about a vertical axis, said agitator underlying the clothing in said tub, and means carried by said agitator and actuated by the oscillation thereof for discharging liquid laterally from beneath the margin of the agitator whereby ingress of articles of clothing beneath the agitator is opposed.

3. In a clothes washing machine, in combination, a tub, an agitator located therein and oscillatable about a vertical axis, said agitator comprising a circular plate having its margin adjacent to the tub bottom, projecting elements carried by the top face of the plate, and means carried by said plate and actuated by the oscillation thereof for discharging liquid laterally from beneath its margin whereby ingress of articles of clothing beneath the agitator is opposed.

4. In a clothes washing machine, in combination, a tub, an agitator located therein and oscillatable about a vertical axis, said agitator comprising a circular plate having its margin adjacent to the tub bottom, projecting elements carried by the top face of the plate and blades beneath said plate adapted to displace liquid centrifugally as the agitator is oscillated, said plate being apertured at a distance from its margin for admission of washing liquid.

5. In a clothes washing machine, in combination, a tub, an agitator located therein and oscillatable about a vertical axis, said agitator comprising a circular plate having its margin adjacent to the tub bottom, projecting elements carried by the top face of the plate, said plate having one or more apertures for washing liquid at a distance from its margin, and blades beneath said plate for forcing such liquid laterally out across the tub bottom.

6. In a clothes washing machine, in combination, a tub, an agitator comprising a metal plate covering only a portion of the tub bottom and provided with a socket opening through one face for the operating shaft, said plate having apertures therein for the passage of washing liquid therethrough, and means operative upon oscillation of said agitator for causing an outflow of liquid from beneath said plate.

7. An agitator for clothes washing machines comprising a circular metal plate having at its center a socket whose axis is substantially normal to the plane of the plate, clothes-rubbing and liquid-agitating provisions on the opposite side of said plate from the socket, and radial blades on the same side of said plate with said socket, said plate having apertures between said blades.

8. An agitator for clothes washing machines comprising an upwardly facing metal plate having a socket on its lower face for an operating shaft and also having apertures therethrough, and means for causing washing liquid to flow through said apertures from the upper to the lower face of said plate as the agitator is oscillated and to be discharged around the margin of said agitator. 5
9. An agitator for clothes washing machines comprising a circular plate having liquid-agitating and clothes-rubbing provisions on one face and a socket opening through the other face, a circular shield plate concentric therewith and spaced from the last named face, and radial vanes between said plates, said first plate being apertured for ingress of washing liquid and said second plate having its margin spaced from the margin of said 10 first plate for the egress of such liquid. 15
10. In a washing machine, a tub, an agitator located inside said tub having clothes-rubbing provisions on its upper face, said agitator located closely adjacent the bottom 20 of the tub, and being apertured for the passage of liquid therethrough, means for oscillating said agitator, and means carried by said agitator and operative by said oscillation for drawing liquid in through such aperture or apertures and discharging it laterally across the tub bottom from beneath the margin of said agitator whereby entrance of clothing beneath said agitator is opposed. 25
11. In a clothes washing machine, in combination, a casing, and a dasher journaled therein, said dasher having a circular disk adjacent to the casing bottom, a plurality of radial vanes carried by the upper face of said disk, and a second disk located on top of said 30 vanes, said second disk having blades on its upper face and also having a central, hollow elevated portion formed with water-admitting apertures. 35
12. In a clothes washing machine, in combination, a casing, and a dasher journaled therein, said dasher comprising a pair of vertically-spaced, concentric, circular disks, and radial vanes between said disks, the upper disk having an elevated hollow portion 40 formed with external ribs and perforations between the ribs. 45
13. In a clothes washing machine, in combination, a casing, and a dasher journaled therein, said dasher having a circular disk adjacent to the casing bottom, means for oscillating said dasher, and means operative during the oscillation for producing a radial discharge of liquid adjacent one face of the disk. 55
14. In a clothes washing machine, a tub, an agitator located inside said tub and comprising a circular plate having its margin adjacent to the tub bottom, the side wall of the tub being spaced away from the margin of 60 said plate, and the tub bottom being formed 65
- between said plate and side wall with an annular depression which is lower than the portion covered by the agitator and is adapted to catch foreign bodies as buttons and pins. 70
15. In a clothes washing machine, a tub, an oscillatable dasher mounted therein upon a vertical axis, said dasher having a central socket opening downwardly, a driving shaft traversing the bottom of said tub and having its upper end fitting in said socket, said dasher having a circular disk portion which extends laterally in all directions adjacent the bottom of the tub, blades carried by the upper face of said disk, and radial vanes carried by the lower face of said disk. 75
16. In a clothes washing machine, a tub, an oscillatable dasher mounted therein upon a vertical axis, said dasher having a central socket opening downwardly, a driving shaft 80 traversing the bottom of said tub and having its upper end fitting in said socket, said dasher having a circular disk portion which extends laterally in all directions adjacent the bottom of the tub, blades carried by the upper face of said disk, and radial vanes carried by the lower face of said disk. 85
17. An agitator for clothes washing machines having a central socket for a driving shaft, a circular disk to underlie the clothes coaxial with said socket, blades on the top face of said disk to agitate the clothes, and blades on the bottom face of said disk to keep clothes out from beneath. 90
18. An agitator for clothes washing machines having a central socket for a driving shaft, a circular disk to underlie the clothes coaxial with said socket, blades on the top face of said disk to agitate the clothes, and blades on the bottom face of said disk to keep clothes out from beneath, said dasher having perforations near its axis to permit washing liquid to circulate downwardly near the center and outwardly between said vanes. 95
